UNITED STATES PATENT OFFICE.

EMIL HERBECK, OF HALLSTEAD, PENNSYLVANIA.

DESIGN FOR A CUT-GLASS VESSEL OR SIMILAR ARTICLE.

41,955.

Specification for Design.

Patented Dec. 5, 1911.

Application filed July 26, 1911. Serial No. 640,707. Term of patent 3½ years.

To all whom it may concern:

Be it known that I, EMIL HERBECK, a citizen of the United States, residing at Hallstead, in the county of Susquehanna and State of Pennsylvania, have invented a new, original, and ornamental Design for a Cut-Glass Vessel or Similar Article, of which the following is a specification, reference being had to the accompanying drawing, forming part thereof.

Figure 1 is a plan view of a cut glass vessel showing my new design. Fig. 2 is a side elevation thereof.

I claim:—

The ornamental design for a cut glass vessel or similar article as shown.

EMIL HERBECK.

Witnesses:

CHAS. L. CROOK,
LOUISE C. HERBECK.
